UNITED STATES PATENT OFFICE.

MARGUERITE L. STONE, OF SAN FRANCISCO, CALIFORNIA.

DESIGN FOR A DOLL.

Application filed November 15, 1921. Serial No. 515,418. Term of patent 3½ years.

To all whom it may concern:

Be it known that I, MARGUERITE L. STONE, a citizen of the United States, residing in the city and county of San Francisco and State of California, have invented a new, original, and ornamental Design for Doll, of which the following is a specification, reference being had to the accompanying drawings, forming part thereof.

Fig. 1 is a perspective front view of the doll.

Fig. 2 is a perspective rear elevation of the doll.

I claim:

The ornamental design for a doll, as shown.

MARGUERITE L. STONE.

Witnesses:

R. B. NEWBRE,
EUGENE P. JONES.
